United States Patent Office

Des. 188,848
Patented Sept. 20, 1960

188,848

RECORDING OSCILLOGRAPH

John P. Mahoney, Wheatridge, and Tommy N. Tyler,
Littleton, Colo., assignors to Minneapolis-Honeywell
Regulator Company, Minneapolis, Minn., a corpora-
tion of Delaware

Filed Apr. 29, 1960, Ser. No. 60,372

Term of patent 14 years

(Cl. D26—1)

The single figure is a front perspective view of a recording oscilloscope, showing our new design.

The opposite side, not shown, is substantially a mirror image of the side shown, and the rear not shown, is conventional.

We claim:

The ornamental design for a recording oscilloscope, substantially as shown and described.
